BOX OR SIMILAR ARTICLE

Stanley Bindman, Roslyn Heights, N.Y., assignor to Jamison Plastics Corp., North Bellmore, N.Y., a corporation of New York

Filed Oct. 26, 1959, Ser. No. 58,064

Term of patent 14 years

(Cl. D58—12)

Fig. 1 is a top plan view of a box showing my new design;

Figs. 2, 3 and 4 are front, side and back views, respectively, thereof; and

Fig. 5 is an enlarged fragmentary cross-sectional view taken on line 5—5 of Fig. 2;

The side of the box not shown is the same as the side shown; the bottom is plain.

The characteristic feature of my design resides in the ornamentation of the top wall of the box.

I claim:

The ornamental design for a box or similar article, substantially as shown and described.
